UNITED STATES PATENT OFFICE.

SAMUEL K. HAWKINS, OF NEW YORK, N. Y.

DESIGN FOR A SCRUBBING-BRUSH.

SPECIFICATION forming part of Design No. 26,154, dated October 6, 1896.

Application filed July 30, 1896. Serial No. 601,100. Term of patent 3½ years.

To all whom it may concern:

Be it known that I, SAMUEL K. HAWKINS, a citizen of the United States, residing at New York city, in the county and State of New York, have invented and produced a new and original Design for Scrubbing-Brushes, of which the following is a specification, reference being had to the accompanying drawing, forming a part thereof, which represents a perspective view of a scrubbing-brush embodying the novel features of the design.

The design consists in the sides of the brush-back, and a compound curve approximating

an S-curve, each end of the brush-back terminating in a well-defined point. The upper 15 edge of each side is chamfered, the chamfer being carried from point to point, while in plan view the back is plain.

I claim—

A design for a scrubbing-brush, substantially as herein shown and described.

SAMUEL K. HAWKINS.
